FLUID PRESSURE BRAKING APPARATUS

William E. Wine, Toledo, Ohio

Application October 18, 1935, Serial No. 45,665

11 Claims. (Cl. 188—195)

My invention relates to fluid pressure braking apparatus for railway and other vehicles and more particularly to mechanism for automatically varying the braking power of the system according to the light or loaded condition of the vehicle.

One of the principal objects of the invention is to provide simple and efficient means which is only operable upon an increase of the fluid pressure of the brake system from a low or uncharged condition for varying the braking power of the system.

Another object of the invention is to provide simple and reliable means for automatically varying the leverage ratio of the brake rigging of a railway car according to the light or loaded condition of the vehicle.

Other objects and advantageous features of the invention will hereinafter appear and be fully pointed out in the claims.

In the drawings:

Figure 1 is a diagrammatic view illustrating the invention applied to a railway car of the hopper type, the mechanism being shown in the position it normally assumes when the car is empty and conventional parts of the brake system of such cars being shown in dotted lines.

Figure 2 is an enlarged sectional view of the main parts of the mechanism in their normal positions which approximately correspond to the positions they occupy when the car is loaded, the parts being shown in juxtaposition for convenience of illustration.

Figure 2a is a view, partly in section and partly in elevation, illustrating the lower end of the plunger of the control valve and adjacent portions of the car.

Figures 3 and 4 are sectional views of the change-over valve mechanism showing the parts thereof in different operative positions.

Figures 5 and 6 are sectional views of the control valve showing the parts thereof in different operative positions.

Figure 7 is an elevational view of the mechanism for varying the leverage ratio of the brake rigging, the mechanism being in the position it occupies when the car is empty.

Figure 8 is an end view of the mechanism illustrated in Figure 7.

Figure 9 is a sectional view taken on a line corresponding to line 9—9 of Figure 7, the parts being shown in the position they occupy when in the position shown in dotted lines in Figure 7.

Figure 10 is a diagrammatic sectional view of a portion of a railway car truck provided with a

member for cooperating with means associated with the control valve.

Referring more particularly to the drawings, the apparatus comprises in general a change-over valve mechanism 1, a control valve 2 and an operating cylinder 3. The conventional parts of a railway brake system illustrated in dotted lines in Figure 1 includes a train pipe 4, a triple or distributing valve 5, an auxiliary reservoir 6, a brake cylinder 7 and the pipes connecting these various parts.

The change-over valve mechanism 1 comprises a casing 8 having a port 9 which is in open communication with the train line pipe 4 by means of a pipe 10. Fluid pressure entering port 9 escapes into the casing 8 through relatively small apertures 11. Slidably mounted within the casing are two valves 12 and 13, respectively, and so that they may be responsive to and operable by the fluid pressure, the stem of each is preferably provided with a flexible diaphragm or the like 14.

Slide valve 12 controls the passage of fluid pressure from the change-over valve mechanism to the control valve 2 and a spring 15 is provided to maintain the slide valve in a position (see Figure 2) enabling the flow of fluid pressure through a pipe 16 to the control valve until the pressure within the casing 8 exceeds a predetermined value. After the pressure within the casing 8 exceeds this predetermined value, slide valve 12 is caused to move into a position (see Figures 3 and 4) preventing the flow of fluid to the control valve and, when in this position, the cavity 17 with which the valve is provided connects pipe 16 with an atmospheric port 18, whereby the fluid within the control valve is exhausted. The port 18 may, if desired, be provided with a pipe or the like 18a in open communication with the atmosphere.

Slide valve 13 controls the flow of fluid pressure from the casing 8 through a pipe 19 to the operating cylinder 3. Mechanism, to be herein-after described, is provided for normally preventing movement of valve 13 by the fluid pressure and to maintain it in a position (see Figure 2) preventing the flow of fluid from casing 8 to the operating cylinder. When in this position, the valve, by means of a cavity 20, functions to connect the operating cylinder 3 to a port 21, which is in open communication with atmospheric port 18.

The mechanism normally preventing movement of slide valve 13 may advantageously consist of a cylindrical bolt or the like 22, which is slidably mounted within a chamber 23 located at

the outer end of the stem 24 of the valve. The bolt 22 is provided with an aperture 25 which is adapted to be brought into registry with the stem 24 to permit movement of the slide valve under the influence of the fluid pressure within the casing 8 into a position (see Figure 4) permitting the passage of fluid from casing 8 through pipe 19 to the operating cylinder 3. The bolt 22 is normally maintained in a position preventing movement of slide valve 13 by a spring 26 which may be conveniently disposed within chamber 23. The bolt is adapted to be moved into a position enabling movement of slide valve 13 by fluid pressure and, for this purpose, it may be advantageously provided with a flexible diaphragm 27 disposed within a chamber 28 having communication through a pipe 29 with a valve controlled port of the control valve 2.

The control valve comprises a casing 30 in which is slidably mounted a plunger 31 adapted to be operated by the fluid pressure of the brake system. While the plunger may be provided with any suitable fluid pressure responsive means, it is preferably provided intermediate its ends with a flexible diaphragm 32 and encircling one end of the plunger is a spring 32a for normally maintaining it in inoperative position, as shown in Figure 2. The upper end of the plunger is of reduced cross sectional area and mounted thereon between shoulders or the like 33 and 34, respectively, is a relatively slidable valve 35 for controlling the passage of fluid pressure to chamber 28 in which the diaphragm for actuating the bolt 22 is disposed. When the plunger is in its elevated inoperative position (see Figure 2), slide valve 35 is disposed in a position so that cavity 36 with which it is provided connects pipe 29 leading to chamber 28 to an atmospheric port 37. Upon actuation of the plunger by the fluid pressure, the shoulder 33 at the end of the plunger is adapted to engage the slide valve and move it into a position (see Figure 6) uncovering the port leading to pipe 29, thus permitting the passage of fluid pressure into chamber 28 for operating bolt 22.

Plunger 31 of the control valve is provided with an extension, preferably in the form of a detachable rod or pin 38, for cooperating with an unsprung part of the car which, since the control valve is mounted on the car body, is capable of assuming different positions with respect to the control valve depending upon the light or loaded condition of the car. In the present embodiment of the invention wherein it is shown as being applied to a railway hopper car, the control valve 2 is secured to one of the body bolsters 39 of the car so that the extension 38 of the plunger is movable vertically and extends downwardly through an opening formed in the top of the center sill 40 of the car for cooperating with means 41 extending through a bore formed in the king pin 42 of the adjacent car truck. Means 41 comprises a rod, preferably formed in two sections for convenience of assembly, the lower end of which extends through an opening formed in the bottom wall 43 of the truck bolster 44 and rests upon and is supported by a member 45 secured to the side frames 46 of the truck. It will thus be appreciated that the distance between the lower end of rod 38 of the control valve 2 and the upper end of the rod 41 will vary in accordance with variations of the load in the vehicle. Accordingly the extent of movement of plunger 31 of the control valve is determined by the loaded condition of the car and the various parts of the control valve are so

formed and proportioned that it is only when the car is unloaded that the plunger may be moved a sufficient distance to cause valve 35 to uncover the port communicating with pipe 29 leading to chamber 28.

The operating cylinder 3 comprises a casing 48 in which is slidably mounted a tubular sleeve 49, the inner end of which is interiorly threaded to receive a head or plug 50 by which a rod 51 is connected to the sleeve. The inner end of the rod is enlarged to provide a head 52 which engages behind an internal rib 53 of the sleeve and, in order to permit the rod to angle with respect to the sleeve, the enlarged head is formed as a substantially spherical knob which fits within a suitably shaped recess in the head or plug 50. Instead of providing the sleeve with a conventional piston, it is preferred to employ a collapsible and expansible bellows 54, to the inner end of which the head or plug 50 is secured as by welding. Interposed between the bellows 54 and the sleeve 49 and encircling the latter is a helical spring 55 for normally maintaining the sleeve and the associated rod 51 in their innermost positions in the cylinder.

Rod 51 of the operating cylinder is connected to mechanism for varying the leverage ratio of the brake rigging. This mechanism includes a brake lever of the type disclosed and claimed in my co-pending application Serial No. 8,372, filed February 26, 1935, which is formed in two sections 56 and 57, respectively, section 56 being pivotally mounted on a bracket 58 rigidly secured to a suitable portion of the car and section 57 being pivotally connected to the opposite end of section 56. The end of section 57 opposite the one pivotally connected to section 56 is connected to a brake rod 59 and, at an intermediate point, it is connected to the piston rod of the brake cylinder 1. Section 56 of the lever is preferably formed with two laterally spaced coextensive plate-like portions 60 which are rigidly connected at their lower ends by a transverse web 61 adapted to engage the inner edge of section 57 below the point of pivotal connection of the two sections. Due to this construction, it will be perceived that, when the piston rod of the brake cylinder is moved outwardly in a brake applying direction, the two sections of the lever will move as a substantially rigid unit to transmit a braking force to the brake rod 59.

To cause section 57 of the brake lever to move independently of section 56 about the pin connecting them and, to thereby decrease the braking leverage, means is provided which is operable by the operating cylinder 3 for restraining movement of lever section 56. This means comprises a member 62 which extends between the spaced plate portions 60 of lever section 56, the outer end of which is provided with oppositely projecting bosses or the like 63, which are adapted to engage the outer side edges of adjacent portions of the plate portions 60 within recesses 64. Extending axially through the bosses 63 is a pin 65 pivotally connecting member 62 to a pair of links 66 which are pivotally mounted on bracket 58 by the same pin connecting lever section 56 thereto.

Member 62 is actuated to move the bosses 63 thereof into and out of cooperative association with lever section 56 by a bell crank lever 67, which is journaled within a downwardly extending bifurcated portion 68 of bracket 58 and has two pairs of arms 69 and 70, arms 69 being pivotally connected to the inner end of member 62 and arms 70 being pivotally connected to a mem- 75

ber 71 screw threaded upon the outer end of rod 51 of the operating cylinder.

The member 62 is offset intermediate its ends, as indicated at 72, so that, when the fluid pressure of the brake system has actuated the expandable and contractable bellows 54 to project the rod 51 out of the cylinder and thus operate member 62 to bring it into position for preventing movement of lever section 56, a line joining the axes of the 10 means pivotally connecting member 62 to links 66 and arms 69 of bell crank 67 will pass beneath the pivotal axis of the bell crank. Lever section 56, therefore, instead of tending to rotate the bell crank in a direction which would result in moving 15 member 62 into an inoperative position, tends to rotate the bell crank in the opposite direction. Although cylinder 3 is operatively associated with member 62 in such manner that, when fluid pressure is admitted to the cylinder, member 62 is 20 moved from an inoperative position into a position in which it is operative to restrain movement of lever section 56, it will be readily appreciated that the parts may be easily rearranged so as to produce the opposite result, namely, to move 25 member 62 from a position in which it is operative to engage lever section 56 into a position in which it is inoperative to engage this section.

Due to the slack in the brake rigging of all railway cars, it is preferred that lever section 56 will 30 not be restrained from movement by member 62 until after all of the slack in the brake rigging has been taken up. Accordingly, as shown in Figure 7, sections 56 and 57 of the brake lever always move as a rigid unit to take up slack and 35 it is not until after the lever has assumed a position, the dotted line position shown in Figure 7, in which the slack has been taken up that member 62 is capable of arresting movement of section 56.

The operation of the apparatus is as follows: Assuming that the brake system is at atmospheric pressure, the various parts of the change-over valve mechanism 1, the control valve 2 and the operating cylinder 3 will be in the positions 40 shown in Figure 2. As soon as fluid under pressure is supplied to train pipe 4, it will flow through pipe 10 into casing 8 of the change-over valve mechanism and thence through pipe 16 into the control valve 2. Plunger 31 of the control valve is then caused to move downwardly and the extent to which the plunger may be moved is controlled by the position of the rod 41 extending upwardly through the king pin 42. If the car is loaded or nearly so, the upper end of 45 rod 41 will be disposed in a position closely adjacent the lower end of rod 38 of the plunger, such as shown in dotted lines in Figure 2a, and the plunger, therefore, may be only moved a limited distance into a position, such as shown in Figure 5. If the car is unloaded or nearly so, that is light, the upper end of rod 41 will be disposed at a greater distance from the lower end of rod 38 of the plunger of the control valve, so that the plunger may be moved a greater 50 distance and sufficient to move slide valve 35 into the position shown in Figure 6.

When the car on which the apparatus is installed is loaded and the fluid pressure admitted into the control valve is, therefore, not capable 55 of moving plunger 31 thereof a sufficient distance to move slide valve 35 to uncover the port with which pipe 29 communicates, fluid pressure will not be admitted to chamber 28 and bolt 22 will not be operated to enable movement 60 of valve 13 by the fluid pressure. After the pres-

sure of the fluid within casing 8 of the change-over valve mechanism exceeds a predetermined value, such, for example, as thirty pounds, the force exerted by spring 15 is overcome and valve 12 is caused to move upwardly into the position indicated in Figure 3, thus cutting off the flow of fluid pressure to the control valve and venting pipe 16 to the atmosphere. Spring 32a encircling plunger 31 of the control valve then functions to return the plunger into its normal inoperative position indicated in Figure 2. A sufficient interval intervenes between the time fluid pressure first passes into the control valve and the time pressure builds up within casing 8 to move the valve 12, so that ample opportunity is 15 afforded for the plunger to be operated by the fluid pressure. Moreover, the spring for returning the plunger to its inoperative position exerts only sufficient force to accomplish this result, which force is considerably less than the 20 force required to operate spring 15 which cooperates with the valve 12. From the foregoing, it will be perceived that, when the car to which the apparatus is applied is fully loaded, fluid pressure is not supplied to the operating cylinder 3 25 and the latter will, therefore, remain in its normal inoperative position illustrated in Figure 2, in which position member 62 is inoperative to restrain movement of lever section 56. The sections of the lever will, therefore, move as a rigid 30 unit to transmit a maximum braking force.

When the vehicle on which the apparatus is installed is empty, or nearly so, sufficient distance intervenes between the lower end of plunger 31 and the upper end of rod 41 to permit the plunger to move far enough to cause slide valve 35 to uncover the port communicating with pipe 29. When the slide valve assumes this position (see Figure 6), fluid pressure within the control valve passes through pipe 29 into chamber 28 where it 35 operates diaphragm 27 to move bolt 22 into a position causing aperture 25 of the bolt to register with stem 24 of slide valve 13. Cooperating with the slide valve 13 is a spring 73 for normally maintaining the valve in the position shown in Figure 2 and, while it is preferred that this spring exert a force substantially the same as spring 15 cooperating with valve 12, so that valve 13 will move at substantially the same instant valve 12 moves, spring 73 may exert a considerably less 40 force than spring 15, but care must be taken that it is not of such capacity that a greater force will be required to actuate valve 13 than valve 12. After bolt 22 has been actuated by the fluid pressure flowing through the control valve and 45 sufficient pressure (the same or less than that required to operate valve 12) has been built up within casing 8 to actuate valve 13, this valve moves into the position shown in Figure 4, uncovering the port communicating with pipe 19 50 and thus enabling fluid to pass into the operating cylinder to cause the mechanism associated therewith to assume the position shown in Figure 1 and also in full lines in Figure 7.

As soon as the pressure in casing 8 exceeds the 55 predetermined value heretofore mentioned, slide valve 12 is again actuated and moved into the position shown in Figure 4, thus cutting off the supply of fluid pressure to the control valve and enabling the plunger to move upwardly under the 60 influence of spring 32a into the position shown in Figure 2. In this position, pipe 29 is vented to the atmosphere through cavity 36 of slide valve 35 and atmospheric port 37, thus exhausting the 65 pressure from chamber 28. Bolt 22 is, however, 70

prevented from moving under the influence of spring 26 into the position shown in Figure 2, due to the stem 24 of slide valve 13 being disposed within the aperture 25 of the bolt. It will be appreciated that so long as the pressure of the fluid within casing 8 is maintained at such value preventing return of slide valve 13 by spring 73 into the position indicated in Figure 2, fluid pressure will be supplied to operating cylinder 3 to maintain it in the position illustrated in Figure 1. In this position, the mechanism with which the operating cylinder cooperates functions to restrain movement of section 56 of the brake lever and accordingly the braking leverage is reduced and thus less braking power is available for braking an empty car than a loaded car.

When the fluid pressure of the brake system is exhausted, as by uncoupling the car from a train, the two slide valves of the change-over mechanism will return into the positions indicated in Figure 2. When slide valve 13 assumes the position there indicated, cavity 20 thereof connects pipe 19 to atmospheric port 18, so that rod 51 of the operating cylinder is always enabled, when there is no fluid pressure in the system, to return under the influence of spring 55 to the position indicated in Figure 2 wherein the brake lever cooperating mechanism is set in a position enabling the brake lever to transmit a maximum braking force.

From the foregoing, it will be apparent that a simple and reliable apparatus has been provided for varying the braking power of a fluid pressure braking system according to the light or loaded condition of the vehicle, which is only operable during the interval the pressure of the system increases from a low or uncharged condition to a predetermined value and is incapable of operation as long as the pressure does not drop below the predetermined value. Moreover, as the predetermined value is one below which the fluid pressure of the braking system of the vehicle on which the apparatus is installed will not drop during normal operation of the vehicle, the braking power of the system initially established by the apparatus will not vary under normal operating conditions of the vehicle.

It will be evident to those skilled in the art that the invention is not limited to use with means for changing the leverage ratio of the brake rigging to vary the braking power of the system and that it is capable of use with other and perhaps more conventional means for varying the braking power of a fluid pressure system.

55 What is claimed is:

1. In combination with a fluid pressure brake system for a vehicle, fluid pressure operated means for varying the braking power of the system, valve means operable by the fluid pressure for controlling the operation of said means, mechanism controlling the operation of said valve means including a device movable by the fluid pressure according to the light or loaded condition of the vehicle, and additional valve means responsive to the fluid pressure and operable upon a predetermined increase in said pressure to shut off the flow of fluid to said device.

2. In combination with a fluid pressure brake system for a vehicle, fluid pressure operated means for varying the braking power of the system, valve means subject to the fluid pressure for controlling the flow of fluid pressure to said means, movable means normally adapted to be engaged by said valve means for preventing movement of the latter by the fluid pressure, and means

for controlling the operation of said movable means including a device movable by the fluid pressure according to the light or loaded condition of the vehicle.

3. In combination with a fluid pressure brake system for a vehicle, fluid pressure operated means for varying the braking power of the system, valve means subject to the fluid pressure for controlling the flow of fluid pressure to said means, movable means normally preventing movement of said valve means in one direction, pressure responsive means for actuating said movable means, and a device movable by the fluid pressure according to the light or loaded condition of the vehicle for controlling the flow of fluid to said pressure responsive means.

4. In combination with a fluid pressure brake system for a vehicle, fluid pressure operated means for varying the braking power of the system, valve means constantly subject to the fluid pressure for controlling the flow of said fluid to said means, movable means normally locking said valve means against movement by the fluid pressure, pressure responsive means for causing said movable means to assume a position permitting movement of said valve means by the fluid pressure, and a device movable by the fluid pressure according to the light or loaded condition of the vehicle for controlling the flow of fluid to said pressure responsive means.

5. In combination with a fluid pressure brake system for a vehicle, fluid pressure operated means for varying the braking power of the system, valve means subject to the fluid pressure for controlling the operation of said means, movable means normally locking said valve means against movement by the fluid pressure, and mechanism responsive to the fluid pressure and movable thereby according to the light or loaded condition of the vehicle for controlling movement of said movable means to an inoperative position, said valve means after assuming open position upon movement of the movable means to inoperative position being cooperable with the movable means to maintain the latter in inoperative position independent of said mechanism.

6. In combination with a fluid pressure brake system for a vehicle, means adapted to be actuated by the fluid pressure for varying the braking power of the system, a valve normally disposed in closed position preventing the flow of fluid pressure to said means, means subject to the fluid pressure for moving said valve to open position, movable means normally preventing movement of the valve to open position, pressure responsive means adapted to be subjected to the fluid pressure for causing said movable means to assume a position enabling said valve to move to open position, and a device movable by the fluid pressure according to the light or loaded condition of the vehicle for controlling the flow of fluid to said pressure responsive means.

7. In combination with a fluid pressure brake system for a vehicle, means adapted to be actuated by the fluid pressure for varying the braking power of the system, valve means movable by the fluid pressure for controlling the flow of fluid to said means, movable means cooperable with said valve means normally preventing movement thereof by the fluid pressure, mechanism for controlling the operation of said movable means including a device movable by the fluid pressure according to the light or loaded condition of the vehicle, and additional valve means responsive to the fluid pressure and operable upon a predetermined increase in said pressure to shut off the flow of fluid to said device.

mined increase in said pressure to shut off the flow of fluid to said device.

8. In combination with a fluid pressure brake system for a vehicle, fluid pressure operated means for varying the braking power of the system, a device movable by the fluid pressure to determine the light or loaded condition of the vehicle, a plurality of valve means each subject to the fluid pressure, one of said valve means being operable upon a predetermined increase in the fluid pressure to shut off the flow of fluid to said device and the other of said valve means controlling the flow of fluid to the means for varying the braking power of the system, movable means normally restraining movement of said last named valve means, and fluid pressure means operable according to the extent of movement of said device for causing said movable means to assume a position permitting movement of the last named valve means.

9. In combination with a fluid pressure brake system for a vehicle, valve means adapted to be moved by the fluid pressure of the system for adjusting the braking power of the system according to the light or loaded condition of the vehicle, movable means normally restraining movement of the valve means by the fluid pressure, fluid pressure operated means for causing said movable means to assume a position enabling movement of the valve means, and a device movable by the fluid pressure according to the

light or loaded condition of the vehicle for controlling the flow of fluid to said pressure operated means.

10. In combination with a fluid pressure brake system for a vehicle, valve means for adjusting the braking power of the system according to the light or loaded condition of the vehicle, said valve means being constantly subject to the fluid pressure of the system and adapted to be moved thereby, movable means adapted to be operated by the fluid pressure normally preventing movement of said valve means, and mechanism for controlling the supply of fluid pressure to said movable means, said mechanism including a device movable by the fluid pressure into different positions according to the light or loaded condition of the vehicle.

11. In combination with a railway car brake rigging and a fluid pressure system for operating the brake rigging, movable means for varying the leverage ratio of the brake rigging, a fluid pressure operated device for actuating said movable means, valve means for controlling the flow of the fluid pressure in the system to said device, and means including a device responsive to the fluid pressure of the system and movable thereby into different positions according to the light or loaded condition of the car for controlling the operation of said valve means.

WILLIAM E. WINE.
